(57) **CLAIM**

The ornamental design for an obturator for a projectile cartridge as shown and described.

DESCRIPTION

FIG. 1 is a perspective view of an obturator for a projectile cartridge showing the claimed design;

FIG. 2 is side view thereof;

FIG. 3 is a second side view of thereof;

FIG. 4 is a top view of thereof; and,

FIG. 5 is a bottom view of thereof.

The broken lines show portions of the obturator for a projectile cartridge that form no part of the claimed design. The unshaded area between solid and broken line structure forms no part of the claim.

1 Claim, 3 Drawing Sheets
